UNITED STATES PATENT OFFICE

HENRY G. LYKKEN, OF MINNEAPOLIS, MINNESOTA

MATERIAL REDUCING AND CLASSIFYING DEVICE

Application filed March 29, 1929. Serial No. 350,995.

The present invention relates to the reducing of material to a fine state, and also the proper conditioning of the same for use.

Among the objects of the invention is to provide a novel device for and a novel method of reducing materials, the material to be reduced being subjected to a vorticose movement of a reducing fluid, which is produced evenly against the body of material to effect a uniform reduction of the particles of material.

The invention comprehends the idea of positioning the means for producing the vorticose movement relative to the body of material to be reduced, to cause the vorticose movement of the reducing fluid to act evenly against the body of material, so that the particles, by reason of rubbing upon each other under the uniformity of stresses imparted by the vorticose movement, to be more uniformly reduced, and to be uniformly distributed in the reducing fluid.

The invention is applicable to the reducing of any reducible material, but for illustration it is herein described as a fuel device and therefore has for an object the provision of a novel fuel reducing device in which the fuel is uniformly reduced and converted into a fluidal condition and mixed with a supporter of combustion, such as air. It also comprehends the idea of utilizing a fluid such as air, to effect the substantial uniform or even reducing of the material by an act similar to fluid erosion. The material laden fluid body is then directed to means where it is acted upon to obtain the degree of fineness and the degree of concentration desired, and is then directed to the locus or loci of consumption in a state of uniformity, according to the demand at those loci.

Another object of the invention is to provide a novel means for directing the uniform or equal fluidal stream into the chamber and into the region of the vorticose movement. In the illustrative embodiment of the invention, an outer chamber is provided for directing a fluidal or reducing body, such as air, to a multiplicity of points around the blades of an impeller or band member. The fluidal or reducing body is then directed by the action

on the impeller into the region of the vorticose movement, at which point it acts upon the material body evenly to cause an attrition of the material particles and to cause the attrited material particles to become uniformly distributed in the fluidal or reducing body. The resulting material laden body is then directed to means where it is acted upon to obtain the degree of fineness and the degree of concentration desired, the larger and heavier particles being thrown out of the body and directed back into the chamber to be re-reduced.

The invention further comprehends the provision of a novel means for positioning the material in the chamber, relative to the region of the vorticose movement, in order that the particles of the material may be acted upon evenly, by the vorticose movement of the reducing fluid to effect a uniform reduction of the particles in the body. In the embodiment selected to illustrate the invention, a corrugated wall is positioned in association with the walls of the chamber to retard the movement of the material in the chamber, the fan or impeller acting to pile or build up the material about the walls of the chamber, the surfaces of the body being in such a position as to be acted upon evenly by the vorticose movement.

The invention further comprehends the provision of means for feeding the material into the region of the vorticose movement uniformly.

Other objects, advantages, features and capabilities are comprehended by the invention as will later appear, and are inherently possessed thereby.

Referring to the drawings:

Fig. 1 is a view in vertical cross section through a device constructed in accordance with the invention and connected to a separating or classifying device.

Fig. 2 is a horizontal cross sectional view taken in a plane or planes represented by the line 2-2 of Fig. 1.

Referring now more in detail to the drawings, the embodiment selected to illustrate the invention is shown as comprising a reducing chamber 1 in which is rotatably sup-

ported a rotor 2 having radial projections 3 upon which are removably mounted blades 4, the rotor being mounted upon a shaft 5 journaled in a bearing 6 on the bottom wall of 5 the chamber 1, and operated by a suitable source of power.

At one side of the chamber is provided a hopper 7 in which material 8 may be held and charged into the lower part 9 of the chamber, 10 the material therein forming a bed beneath the rotor 2.

A uniform amount of material is maintained in the lower part 9 of the chamber 1, by means of a ram feeder having an arm 15 portion 10 extending through the lower portion of a wall of a hopper 7, this arm being connected to a frame 12 positioned below the chamber 1 and the hopper 7, and driven by a pitman or connecting rod 13 connected to the 20 frame 12 and driven by an eccentric 14 keyed to a shaft 15, which in turn is driven by a suitable source of power (not shown). A similar arm 11 is provided and is connected to the frame 12 and extends through the 25 lower part of the wall of the chamber 1. This auxiliary arm 11 is provided to agitate and move the material which is constantly being thrown out from a region of the vorticoe movement back into such region where 30 it is further acted upon by the movement to cause it to be finally pulverized.

The amount of material being fed into the lower portion 9, may be regulated by varying the speed of the shaft 15 or by regulating the 35 length of stroke of the frame 12, and likewise the arm 12. The reciprocating movement of the arm 10 provides a very efficient means for uniformly feeding and uniformly agitating the material in the chamber 1. Other 40 methods of feeding may be used to feed material into the chamber at a uniform rate.

The walls of the lower portion 9 of the chamber 1 may be provided with roughened or corrugated sections 16, the corrugations 45 of which act as anchors for the retarding of the lower and outer layers or portions of the material being caused to move around the chamber in the direction of rotation of the rotor. The building up of the material 50 about the walls of the chamber provides a surface against which the vorticoe movement produced by the blade element 4 of the rotor 2 may act evenly to cause a uniform reduction or a uniform attrition of the particles of material forming the surface part of 55 the bed of material.

A recess 17 in the wall of the lower portion 9 is provided wherein material of a non-friable or non-reducible character is collected, and which may be removed through a bulkhead 18.

A reducing fluid and supporter of combustion is introduced into the chamber 1 through an inlet conduit 19, which fluid is distributed equally around the rotor 2 by

ducts 20 which lead into a fluid inlet box 21, having a circular opening 22 in association with the arm portions 3 of the rotor 2, which arm portions direct or distribute the fluid evenly and uniformly into the region of the vorticoe movement set up by the rotation of the rotor 2. The air or other supporter of combustion introduced through these air ducts into such regions may be preheated or not, as desired. The quantity of reducing fluid entering the chamber may be regulated so that the quantity of material being reduced and likewise the degree of concentration of the material being discharged, may be controlled.

The material is introduced at a uniform rate by the ram feeder where the surface of the bed of material in the chamber 1 comes into contact with the vorticoe movement of the reducing fluid produced by the rotor 2. As the reducing fluid is introduced equally about the rotor around 3, the vorticoe movement of the fluid will act evenly against the particles of material to effect a uniformity in their reduction by the eroding effect of the vorticoe movement. The corrugation of the wall 16 holds the material in such a position relative to the blade element that the material is reduced substantially uniformly over the entire surface. The resulting material-laden fluid body having a substantially uniform distribution of material therein, in a finely divided state, is then passed out through an outlet to a separating and classifying means.

The separating and classifying device is provided with a chamber 23 situated above the chamber 1 of the reducing device, and is separated therefrom by a diaphragm 24 suitably positioned between the ends of the walls 1 and 23 of the reducing and separating chambers respectively. The diaphragm 24 is provided with an opening 25 centrally located and having a skirt portion 26 forming a converging orifice outlet means from the reducing chamber 1 to the classifying or separating chamber 23. The shaft 5 upon which is mounted the rotor 2 in the reducing chamber 1, extends upwardly through the orifice inlet through the chamber 23, and is journaled in suitable bearings 24^a and 25^a connected by any suitable means to a top plate 26 of the chamber 23. A fan or rotor 27 is provided in chamber 23, and is adjustably connected to the shaft 5 by a set screw 28 or the like. A collar 29 connected to the shaft 5 by means of a set screw 30 is provided to more positively position the fan or rotor on the shaft 5.

The fan or rotor 27 and likewise the rotor 2, is rotated by a pulley 31 connected to the shaft 5 at its upper end, and the pulley being in turn driven by a suitable means such as a belt from a suitable source of power (not shown).

A member 32 is provided in the upper portion of the chamber 23 and forms an annular chamber 33 with the walls of the chamber 23 above the fan or rotor 27. The fan 27 is preferably spaced from the diaphragm 24, and when rotated, sets up a vorticose movement in the space between the diaphragm 24 and fan 27, and around the orifice 25 as also in the space between the ends 10 of the blade elements and the walls of the chamber 23, and in chamber 33. The material laden fluid body from the reducing chamber 1 is aspirated up through the orifice means 25 into the separating or classifying chamber 23, where the vorticose movement produced by the fan or rotor 27 will cause a casting off of the heavier and larger particles which impinge upon the lower part 20 of the walls of the chamber 30 and which drop onto the diaphragm 24. The remainder of the fluidal mass continues to swirl in a continuous cyclonic or vorticose path in the direction of the rotation of the fan 27.

A plurality of ports 34 in the diaphragm 24 provide means for diverting the cast-off larger and heavier particles in the material-laden fluid body, back to the reducing chamber 1 to be re-reduced. The size of the ports 34 may be regulated or varied by an annular 30 ring valve 35 on the under side of the diaphragm 24, and slidable upon the annular angle iron 36. The ring valve 35 carries a segmental racket 37 which engages a pinion 38 mounted on a shaft 39 extending through 35 and suitably journaled in the wall of chamber 1, and operated by a hand wheel 40 secured to the exterior end of the shaft.

A plurality of outlet ports, preferably 40 equally distributed, are provided in the top plate 26, and are connected with outlet conduits 41 for distributing the material-laden fluid body to different loci or points of consumption. An annular ring valve 42 carries a segmental rack 42^a meshed with a pinion 42^b on a shaft 42^c suitably rotatably mounted 45 in the wall of chamber 23, the exterior end of the shaft carrying a hand wheel 43. Operating the latter will vary the amount of material-laden fluid body passing through the 50 outlet conduit.

As the reduced material in the fluidal material body assumes a vorticose or cyclonic action in the classifying chamber 23, the coarser and heavier particles are cast out, and then 55 due to the action of gravity, these particles work their way into the collected particles in the chamber. Because of the difference in pressures in the chamber 23 and the reducing chamber 1, there will be a current of air 60 through the ports 34, the current being regulated to draw off and return to the chamber 1, the larger and heavier material particles which have collected upon the diaphragm 24 about the port openings 34.

65 It is possible to obtain a very close control

of the degree of concentration and fineness and of the uniformity of distribution of the material in the material laden fluid body which is being used and consumed at the consuming loci. In the reducing chamber 1, the particles are evenly reduced and uniformly distributed in the reducing fluid and are then aspirated up into the classifying chamber in such a condition, where the heavier and larger particles are cast off and the degree of concentration and the degree of fineness is obtained, after which the material-laden fluid body is distributed to the points of consumption.

While I have herein described and upon the drawings shown an illustrative embodiment of the invention, it is to be understood that the latter is not limited thereto, but comprehends other details, arrangements of parts, features and constructions without departing from the spirit thereof.

Having thus disclosed the invention, I claim:

1. A device for reducing materials, comprising a chamber, a body of material to be reduced in said chamber, means for producing a vorticose movement of a reducing fluid evenly against said body of material, and means for moving certain portions of said body of material uniformly into the locus of the vorticose movement.

2. A device for reducing materials, comprising a chamber, a body of material to be reduced in said chamber, means for directing a reducing fluid into said chamber, and means for producing a vorticose movement of said reducing fluid evenly against said body of material, and means for moving certain portions of said body of material uniformly into the locus of the vorticose movement.

3. A device for reducing materials, comprising a chamber, a body of material to be reduced in said chamber, means for producing a vorticose movement of a reducing fluid evenly against said body of material, and means for positioning said material relative to the locus of the vorticose movement whereby the particles of material are uniformly stressed and reduced.

4. A device for reducing materials, comprising a chamber, a body of material to be reduced in said chamber, means for producing a vorticose movement of a reducing fluid evenly against said body of material, means for positioning said material relative to the locus of the vorticose movement whereby the particles of material are uniformly stressed and reduced, and means for moving certain portions of said body of material uniformly into said locus.

5. A device for reducing materials, comprising a chamber, a body of material to be reduced in said chamber, means for directing a reducing fluid into said chamber, means for

producing a vorticose movement of said reducing fluid evenly against said body of material, and means for positioning said material relative to the locus of the vorticose movement whereby the particles are uniformly stressed and reduced.

6. A device for reducing materials, comprising a chamber, a body of material to be reduced in said chamber, means for producing a vorticose movement of a reducing fluid evenly against said body of material, and means for moving certain portions of said body of material uniformly into the locus of the vorticose movement, and means for collecting and removing particles cast out of said body of material when acted upon by the vorticose movement.

7. A device for reducing materials, comprising a chamber, a body of material to be reduced in said chamber, means for producing a vorticose movement of a reducing fluid evenly against said body of material, and means for equally distributing said reducing fluid into the locus of the vorticose movement.

8. A device for reducing materials, comprising a chamber, a body of material to be reduced in said chamber, means for producing a vorticose movement of a reducing fluid evenly against said body of material, means for equally distributing said reducing fluid into the locus of the vorticose movement, and means for controlling the distribution of reduced material in said reducing fluid.

35 9. A method of reducing materials, comprising the steps of introducing a reducing fluid uniformly over the material for attriting the material and entraining particles of material in the fluid, producing a vorticose movement in the fluid and entrained particles whereby the particles mull against each other to reduce their size, and conducting away the material laden fluid.

10. A method of reducing materials, comprising the steps of introducing a reducing fluid over a body of the material for attriting the material and entraining particles of material in the fluid, producing a vorticose movement of the fluid and entrained particles evenly against the body whereby the particles are uniformly mulled against each other to reduce their size, and conducting away the material laden fluid.

11. A method of reducing materials, comprising the steps of introducing a reducing fluid uniformly over the material for eroding the material and entraining particles of material in the fluid, producing a vorticose movement of the fluid and entrained particles evenly against the body whereby the particles are uniformly mulled against each other to reduce their size, and conducting away the material laden fluid.

12. A device for reducing materials, comprising a reducing chamber, a charging

means leading to the lower part of said chamber and adapted to maintain a bed of material in said chamber, means in said chamber for producing a vorticose movement of a fluid above the surface of the bed of material, and means for feeding the material uniformly into the locus of the vortex.

13. A device for reducing materials, comprising a reducing chamber containing a body of material to be reduced, a rotor in said chamber for producing a vorticose movement of air above the surface of the body of material for driving a current of air against the material, and means in association with the walls of said chamber for positioning the material relative to the locus of the vortex whereby the particles are uniformly stressed and reduced.

14. A device for reducing materials, comprising a reducing chamber containing a body of material to be reduced, a rotor in said chamber for producing a vorticose movement of air above the surface of the body of material for driving a current of air against the material, means in association with the walls of said chamber for positioning the material relative to the locus of the vortex whereby the particles are uniformly stressed and reduced, and means for moving certain portions of said body of material uniformly into said locus.

15. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, and means for uniformly introducing a fluidal body into said chamber in the region of action between said impeller and said body of material.

16. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, means for uniformly introducing a fluidal body into said chamber in the region of action between said impeller and said body of material, and means in association with the walls of said chamber for positioning the material relative to the region of the vortex whereby the particles are uniformly stressed and reduced.

17. A device for reducing materials, comprising a reducing chamber containing a body of material to be reduced, an impeller in said chamber for producing a vorticose movement of a fluid above the surface of the body of material and evenly against said particles for

- effecting reduction in the particles of material in the region of the surface of said body of material, means for uniformly introducing a fluidal stream into said chamber in the region of action between said impeller and said body of material, and means for uniformly moving certain portions of said body of material into said region. 18. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, means for uniformly introducing a fluidal stream into said chamber in the region of action between said impeller and said body of material, means in association with the walls of said chamber for positioning the material relative to the region of the vortex whereby the particles are uniformly stressed and reduced, and means for uniformly moving certain portions of said body of material into said region. 19. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material and inlet means in association with the blade elements of said impeller for uniformly directing a fluidal stream into said chamber in the region of action between said impeller and said body of material. 20. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, inlet means in association with the blade elements of said impeller for uniformly directing a fluidal stream into said chamber and into the region of said vorticose movement, and means associated with the walls of said chamber for positioning the material relative to the region of the vortex, whereby the particles are uniformly stressed and reduced. 21. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, inlet means in association with the blade elements of said impeller for uniformly directing a fluidal stream into said chamber in the region of action between said impeller and said body of material, and means in association with the walls of said chamber for positioning the material relative to the region of the vortex, whereby the particles are uniformly stressed and reduced. 22. A device for reducing materials, comprising a reducing chamber containing a body of material to be reduced, an impeller in said chamber for producing a vorticose movement of a fluid above the surface of the body of material and evenly against said particles for effecting reduction in the particles of material in the region of the surface of said body of material, inlet means in association with the blade elements of said impeller for uniformly directing a fluidal stream into said chamber in the region of action between said impeller and said body of material, and means in association with the walls of said chamber for positioning the material relative to the region of the vortex, whereby the particles are uniformly stressed and reduced, and means for uniformly moving certain portions of said body of material into said region. 23. A device for reducing materials, comprising a reducing chamber, a material holding means connected with the lower part of said chamber and adapted to maintain a body of material in said chamber, a ram feeder adapted to uniformly feed material into said chamber, an impeller in said chamber for producing a vorticose movement of a fluid above the surface of the body of material and evenly against said particles for effecting reduction in the particles of material in the region of the surface of said body of material, inlet means in association with the blade elements of said impeller for uniformly directing a fluidal stream into said chamber and into the region of said vorticose movement, and means associated with the walls of said chamber for positioning the material relative to the region of the vortex, whereby the particles are uniformly stressed and reduced. 24. A device for reducing materials comprising a chamber having means therein for supporting the material to be ground, and a rotor located within said chamber above said material supporting means, so that said material is located below the rotor, said rotor having means for producing a vorticose movement of a fluid against the upper surface of said material so as to reduce the same. 25. A device for reducing materials comprising a chamber having means therein for supporting the material to be ground, a rotor located within said chamber above said material supporting means, so that the material is located below the rotor, means for introducing a reducing fluid into the chamber in the vicinity of the rotor, said rotor having means for producing a vorticose movement

of said fluid against the upper surface of said material so as to reduce the same.

26. A device for reducing materials comprising a chamber, a rotor located within said chamber, said rotor having means for producing a vorticose movement of a reducing fluid within said chamber, and means for feeding material to a position below said rotor so that said fluid will impinge against the upper surface of said material to reduce the same.

27. A device for reducing materials comprising a chamber, means for supporting a bed of material therein, means for introducing a reducing fluid into said chamber, and a rotor mounted in the chamber between said material supporting means and said fluid introducing means so that said material is below the rotor and the reducing fluid is introduced above the same, said rotor having means for producing a vorticose movement of said fluid against the upper surface of said bed of material.

In witness whereof, I hereunto subscribe my name to this specification.
